DELIVERY CONTAINER FOR CIGARETTES,
CIGARS, OR OTHER ARTICLES

Vincent J. Pacione, New York, N. Y.

Application May 22, 1943, Serial No. 488,061

3 Claims. (Cl. 312—79)

This invention relates to boxes adapted to contain cigarettes, cigars, or other articles and to deliver them to a point exterior of the container in a selective and automatic manner, and aims to provide such a device having certain novel and improved features which enhance the practicability and utility of the device.

Another object of the invention is the provision of such a container with means for delivering two distinct articles at the same time from within the container, the delivery mechanism being actuated automatically upon lifting of the cover of the box.

The above and other objects will become apparent in the description below, wherein characters of reference refer to like-numbered parts in the accompanying drawing. It is to be noted that the drawing is intended to serve the purpose of illustration only, and it is neither desired nor intended that the invention be necessarily limited to the exact details of construction shown, excepting insofar as they fall within the spirit and scope of the invention.

Referring briefly to the drawing,

Fig. 1 is a plan view of the box with the cover in open position, with parts broken away to expose the interior.

Fig. 2 is a cross-sectional view taken on the line 2—2 of Fig. 1.

Fig. 3 is a cross-sectional view taken on the line 3—3 of Fig. 1, but showing the cover in closed position.

Fig. 4 is a cross-sectional view taken on the line 4—4 of Fig. 1.

Fig. 5 is a view similar to Fig. 4 but showing the cover in closed position.

Referring in detail to the drawing, the numeral 10 indicates the box or container, which is provided with the bottom 11, front and rear walls 12 and 13, respectively, end walls 14 and 15, and the cover 16 which is hinged to the rear wall 13. Near the end walls 14 and 15 but spaced therefrom and parallel thereto, a pair of support walls 17 are rigidly mounted within the box and are provided with aligned vertical slots 18. Intermediate the width of the box, a partition 19 is mounted parallel with the end walls 14 and 15, and is provided with a vertical slot 20 which is also in alignment with the slots 18 but extends from the bottom of the partition 19 to the yoke 20a near the top of the partition. The partition 19 divides the box into two compartments 21 and 22.

Pivots secured at 23 to the cover 16 are links 24 which hang down into the spaces between the walls 12 and 15 and their respective support walls

17. Secured in the lower extremities of these links and projecting toward each other at right angles to the links, are pins 25. These pins project through and are vertically slidable in the slots 18. A lifter member 26, which comprises a substantially rectangular board-like member in upright position, extending longitudinally between the support walls 17 with its ends registering slidably in vertical grooves 21a in said walls, has recesses in its opposed end edges into which the pins 25 project and are pivotable. A slot 27 is cut out of the upper edge of the member 26 intermediate its length.

In each compartment 21 and 22, a pair of walls 28 are secured to the front and rear walls of the box, near the upper edges thereof, and slope downward toward each other, the lower edges thereof being separated from each other by a longitudinal slot 29 whose opposed walls are parallel and spaced from each other at a distance slightly greater than the thickness of the member 26. The upper edge 30 of the member 26 is arcuately dished out, as shown. It is apparent that the slot 29 serves as a guide to keep the member 26 in vertical positions no matter what the elevation of the same may be. The walls 28 in each compartment 21 and 22 separate these compartments again into an upper compartment or trough 31, above the walls 28, and the space 30 below these walls, to which no reference numeral need be given since that space is not utilized excepting to provide room for the descent of the member 26.

A loose panel 32, substantially rectangular in outline, is laid horizontally on top of the walls 17 and 19 and is supported thereby with its upper surface flush with the upper edges of the end walls 14 and 15. The rear, end corners of this panel are cut away to provide room for the passage of the links 24, as shown at 34, and a thumb nail groove 35 is provided in the upper surface thereof so that it may be more readily lifted out of the box. A pair of aligned slots 33 are cut through the panel so that when it is in position as shown these slots lie directly over the two dished out upper edge (30) portions of the member 26.

In use, the panel 32 is first removed and cigarettes are placed in the two troughs 31, and the panel 32 replaced. Owing to the slope of the walls 28, the cigarettes will tend to roll toward the slot 29. When the cover 16 is closed, the member 26 will have moved down to the position shown in Fig. 5, and since the groove 30 is of sufficient width to seat but a single cigarette at a time, one cigarette will be raised thereon, through the link-

age described, each time the cover is lifted. Since there are two grooves 30, separated by the slot 27, one in each trough 31, a cigarette will thus be delivered on each groove 30. If desired, one compartment 31 might be provided with matches instead of cigarettes or cigars.

Limit stops to the upward movement of the member 26 so that the grooves 30 will rise just high enough to permit the cigarettes therein to be grasped by the fingers, are provided by engagement of the pins 25 with the upper edges of the slots 18. The same limit stops serve to prevent swinging back of the cover 16 to an extreme degree.

Obviously, modifications in form and structure may be made without departing from the spirit and scope of the invention.

I claim:

1. A box comprising front, back, and end walls having a transverse partition intermediate its width, support walls in the box near the end walls thereof, said support walls having vertical slots therein, a cover hinged to said back wall and having links pivotally depending therefrom, pins on the ends of said links passing slidably through said slots, said partition having a vertical slot therethrough extending from the lower edge thereof to a point near the upper edge thereof and in alignment with said first-named slots, an elongated member passing through said partition slot and having said pins registering pivotally in the end edges thereof, said elongated member being substantially rectangular, said partition dividing said box into two compartments, walls secured to the front and back walls of said box in each of said compartments and sloping downward toward each other, the lower

edges of said sloping walls having a slot therebetween, the walls of said last-named slot being parallel and vertical and having said member vertically slidably mounted therein in upright position, the upper edge of said member having a transverse slot therethrough dividing said edge into two sections, the upper edge of each of said sections being arcuately dished out, a loose horizontal panel supported on the upper edges of said 5 support walls and partition and having spaced aligned slots directly above and of substantially the same dimensions as said sections, said compartments above said sloping walls being adapted to have cigarettes or other articles mounted therein, said links when said cover is closed holding said member with said sections thereof horizontally positioned in said sloping wall slots, lifting of said cover to substantially upright position causing said links to raise said member to 10 position said sections to a position substantially flush with said panel slots, the width of said dished-out sections being approximately equal to the thickness of a cigarette so that but one cigarette will be seated on each section when said member is in said lowermost position and said one cigarette will therefore be raised through each of said panel slots upon said lifting of said member to said uppermost position.

2. The device set forth in claim 1, wherein said 15 links pass down into the spaces between said support walls and said end walls of the box, and said pins extend horizontally toward each other.

3. The device set forth in claim 1, wherein said 20 panel is cut away at the rear corners thereof to provide space for the passage of said links.

VINCENT J. PACIONE.
